(57) **CLAIM**

The ornamental design for a tool box, as shown and described.

DESCRIPTION

FIG. 1 is a perspective view of my tool box;

FIG. 2 is a front plan view of my tool box;

FIG. 3 is a top plan view of my tool box;

FIG. 4 is a left side view of my tool box;

FIG. 5 is a bottom plan view of my tool box;

FIG. 6 is a right side view of my tool box; and,

FIG. 7 is a rear plan view of my tool box.

The tool box has a lid that is shaped so as to match the shape and arrangement of the tools in the tool box.
